Inventor

C. W. Smith

By Clarence O'Brien
Attorney

UNITED STATES PATENT OFFICE

CHARLES W. SMITH, OF GREEN ISLAND, NEW YORK

ERASER ATTACHMENT FOR LEAD PENCILS

Application filed January 5, 1928. Serial No. 244,680.

The present invention relates to improvements in eraser tips for lead pencils and has for its principal object to provide a device that includes a means for concealing the 5 eraser tips when not in use, thereby preventing the same from becoming unduly soiled, and thus prolonging the life of the eraser.

A further object of the invention is to provide a device of the above mentioned 0 character wherein the outer end of the eraser tip can be readily and easily exposed for use whenever necessary.

A still further object is to provide an eraser attachment for lead pencils that is 15 simple in construction, inexpensive, strong and durable and further well adapted to the purpose for which it is designed.

Other objects and advantages of the invention will become apparent from the following 20 description when taken in connection with the accompanying drawing.

In the accompanying drawing wherein like reference characters indicate like parts throughout the several views:

25 Figure 1 is a longitudinal sectional view through the attachment embodying my invention showing the outer end of the eraser tip exposed, and

Figure 2 is a side elevation of my attachment showing the tip of the eraser exposed.

In the drawing wherein for the purpose of illustration is shown the preferred embodiment of my invention, the numeral 1 designates an internally and externally threaded 35 barrel that is secured on the upper end of a lead pencil A in any appropriate manner in a fixed position. The eraser indicated at 2 may consist of a stick of rubber or its equivalent. This eraser is secured at its lower 40 end in the upper end of the barrel 1 that projects beyond the upper end of the lead pencil and the lower end of the eraser stick preferably engages the top of the lead pencil in 45 the manner as clearly illustrated in Figure 1.

Cooperating with the externally threaded barrel 1 is the threaded sleeve 4, the same being of a greater length than the barrel and being further formed at its upper end with a 50 reduced unthreaded neck portion 5 that slid-

ably engages the rubber 2 in the manner as clearly illustrated in Figure 1.

By turning the sleeve 4 in one direction, said sleeve will move upwardly on the barrel to cause the upper portion of the neck 5 to 55 extend slightly beyond the upper end or tip of the eraser 2 as indicated by the dotted lines in Figure 1 thereby concealing the top of the eraser and preventing the same from becoming unduly soiled. This will prolong 60 the use of the eraser.

When it becomes necessary to use the eraser, the sleeve 4 is rotated in the reverse direction to cause the same to move downwardly on the barrel 1 and at the same time 65 causing the reduced neck portion 5 to slide downwardly along the rubber stick 2 so that the tip of the eraser will be exposed.

When the sleeve 4 has moved downwardly to its lowermost position, and the upper edge 70 of the reduced neck portion does not uncover the worn down eraser tip, the sleeve may be then rotated in the reverse direction whereby the same will be entirely removed from the barrel. This will permit the fur- 75 ther use of the eraser until the tip of the eraser reaches a point below the upper edge of the barrel that is secured on the end of the pencil.

It will thus be seen from the foregoing de- 80 scription, that I have provided an eraser attachment for lead pencils that is simple in construction and can therefore be manufactured at a very low cost.

While I have shown the preferred embodiment of my invention, it is to be understood that various changes in the size, shape and arrangement of parts may be resorted to without departing from the spirit of the invention and the scope of the appended claim. 85

Having thus described the invention, what I claim as new is:—

In an eraser attachment for lead pencils, a threaded barrel threaded at its lower end 95 on the upper end of a lead pencil and having its upper end portion projecting therefrom, the upper end of the barrel being open, an eraser having its lower end threaded in the upper open end of the barrel for engagement with the upper end of the lead pencil, 100

the barrel being tightly engaged around the eraser throughout the length of the projection portion of said barrel, a sleeve threaded on the barrel and adapted for longitudinal movement thereon, said sleeve being spaced from the eraser, and a reduced unthreaded neck formed on the upper end of the sleeve and slidably engaging the eraser, said neck being adapted to extend beyond the tip of the eraser, to conceal the same when the sleeve is moved upwardly, the tip of the eraser being exposed when the sleeve is moved downwardly and the upper edge of the neck is disposed below the tip of the eraser, said sleeve adapted to be removed from the barrel and said barrel adapted to rigidly support the eraser when the sleeve is removed.

In testimony whereof I affix my signature.
CHARLES W. SMITH.
